(57) **CLAIM**

The ornamental design for an ergonomic handle, as shown and described.

DESCRIPTION

This application claims priority to U.S. Non-Provisional application Ser. No. 11/527,019, filed Sep. 25, 2006.

FIG. 1 is a perspective view of an ergonomic handle showing my new design;

FIG. 2 is a front view thereof;

FIG. 3 is a rear view thereof;

FIG. 4 is a side view thereof;

FIG. 5 is right side elevation view thereof;

FIG. 6 is a top plan view thereof; and,

FIG. 7 is a bottom plan view thereof.

The broken lines form no part of the claimed design.
